Primary Examiner — Robert M Spear*Assistant Examiner* — Eliza Bennett-Hattan(57) **CLAIM**

The ornamental design for a rail top plant hanger, as shown and described.

DESCRIPTION

FIG. 1 is an aerial view of the plant hanger in use on a railing. FIG. 2 is a side elevation view of the plant hanger on rail top showing the position of a plant pot in the hanger.

FIG. 3 is a front elevation view of the plant hanger.

FIG. 4 is a front view of the plant hanger.

FIG. 5 is a bottom view of a plant hanger.

FIG. 6 is a right side view of the plant hanger.

FIG. 7 is a top view of the plant hanger.

FIG. 8 is a left side view of the plant hanger; and, FIG. 9 is a back view of the plant hanger.

The dashed lines showing the plant pot in FIG. 2 depicts environmental subject matter only and form no part of the claimed design.

The house illustration in FIG. 1 forms no part in the claimed design.
